COMBINED DESK PEN SET AND PAPER HOLDER

Ray E. Petit, 248A E. State St., Westport, Conn.

Filed Sept. 29, 1959, Ser. No. 57,721

Term of patent 7 years

(Cl. D74—1)

Fig. 1 is a top perspective view of a combined desk pen set and paper holder showing my new design;

Fig. 2 is a top plan view thereof, the broken line illustration of the writing instrument and receptacle therefor having been eliminated for convenience of illustration;

Fig. 3 is a side elevational view thereof as seen from the left of Fig. 2;

Fig. 4 is a side elevational view as seen from the right of Fig. 2;

Fig. 5 is an end elevational view as seen from the bottom of Fig. 2; and

Fig. 6 is an end elevational view thereof as seen from the top of Fig. 2 when turned at an angle of 180°.

The essential features of the design reside in the portions shown in solid lines on the drawing.

I claim:

The ornamental design for a combined desk pen set and paper holder, as shown and described.
